(57) **CLAIM**

I claim the ornamental design for a 20 sided die for roulette game, as shown and described.

DESCRIPTION

The file of this patent contains at least one drawing/photograph executed in color. Copies of this patent with color drawing(s)/photograph(s) will be provided, by the Patent and Trademark Office upon request and payment of the necessary fee.

FIG. 1 is a top, front, left side perspective view, including grey scale surface shading, showing the 20 sided die for roulette game embodying my new design;

FIG. 2 is a bottom, rear left perspective view thereof, including grey scale surface shading;

FIG. 3 is a front elevational perspective view thereof, including grey scale surface shading;

FIG. 4 is a rear elevational perspective view thereof, including grey scale surface shading;

FIG. 5 is a top, left side perspective view thereof, including grey scale surface shading;

FIG. 6 is a top, front, left side perspective view, with color being claimed as part of the design, showing a second embodiment of the 20 sided die for roulette game embodying my new design;

FIG. 7 is a bottom, rear left perspective view of FIG. 6, with color being claimed as part of the design;

FIG. 8 is a front elevational perspective view of FIG. 6, with color being claimed as part of the design;

FIG. 9 is a rear elevational perspective view of FIG. 6, with color being claimed as part of the design;

FIG. 10 is a top, left side perspective view of FIG. 6, with color being claimed as part of the design;

FIG. 11 is a top, front, left side perspective view, including grey scale surface shading, showing a third embodiment of the 20 sided die for roulette game embodying my new design;

FIG. 12 is a bottom, rear left perspective view of FIG. 11, including grey scale surface shading;

FIG. 13 is a front elevational perspective view of FIG. 11, including grey scale surface shading;

FIG. 14 is a rear elevational perspective view of FIG. 11 including grey scale surface shading;

FIG. 15 is a top, left side perspective view of FIG. 11, including grey scale surface shading;

FIG. 16 is a top, front, left perspective view, with color being claimed as part of the design, showing a fourth embodiment of the 20 sided die for roulette game embodying my design;

FIG. 17 is a bottom, rear left perspective view of FIG. 16, with color being claimed as part of the design;

FIG. 18 is a front elevational perspective view of FIG. 16, with color being claimed as part of the design;

FIG. 19 is a rear elevational perspective view of FIG. 16, with color being claimed as part of the design; and,

FIG. 20 is a top, left side perspective view of FIG. 16, with color being claimed as part of the design.

The grey scale surface shading designates different colored indicia on the faces of the 20 sided die.
